UNITED STATES PATENT OFFICE.

ISAAC KENSEL EVANS, OF HOLLINGER, PENNSYLVANIA.

FUEL FEED FOR WICKLESS BURNERS.

Application filed March 27, 1923. Serial No. 628,113.

To all whom it may concern:

Be it known that ISAAC KENSEL EVANS, a citizen of the United States, residing at Hollinger, in the county of Lancaster and State of Pennsylvania, has invented certain new and useful Improvements in Fuel Feed for Wickless Burners, of which the following is a specification, reference being had therein to the accompanying drawing.

10 This invention relates to an oil feeding device for wickless oil burners, such as are employed for heating brooders, oil stoves and any other uses where a wickless oil burner is used.

15 One of the objects of the invention is to provide means whereby a steady flow of oil is maintained at all times.

20 Another object of the invention is to provide means whereby the flow of oil and the oil level can be regulated without the use of valves.

25 Still another object being that the oil level may be changed by the action of a thermostat, or may be regulated by positive adjustment by the operator.

30 With these and other objects in view my invention consists in certain construction and combination of parts as will hereinafter be fully described and claimed, and shown in the accompanying drawings which form a part of this application and in which like figures of reference refer to corresponding parts in all of the views, but it is fully understood that while I have claimed my 35 invention as shown that I do not confine myself to the exact construction as changes may be made without departing from the spirit of the invention.

40 In the drawings,
Figure 1 is a top plan view of my device as applied to a brooder.

Figure 2 is a side elevation of the same.
Figure 3 is an enlarged view of the controlling means, showing the same as actuated by a thermostat.

45 Figure 4 is a similar view showing the same as actuated by a positive adjustment without the thermostat.

50 Referring to the drawings, the device comprises an oil reservoir 1 of glass or other suitable material here shown as in the form of a bottle, and which may be provided with a band 2 and a bail handle 3 for carrying the same about.

55 The neck 4 of said reservoir 1 is provided with a cap 5 having formed therein the

taper hole 6 for the reception of a tapered plug or stopper 7 which is mounted on a rod 8 which is adapted to slide freely up and down in a bearing 9 formed in a support 10 which is secured to or a part of the cap 5; the plug 7 being normally held in a closed position with relation to the hole 6 by the action of a spring 11; but the lower end of the rod 8 being of such length that when the reservoir 1 is inverted and placed on the top of the oil chamber 12 that the end of said rod 8 will come into contact with the bottom of the chamber 12 in such a manner as to push 70 or force upward the plug 7 and open the hole 6 allowing the oil to feed into said chamber 12.

The oil chamber 12 is formed with a wall 13 dividing said chamber into two parts 14 and 15; said wall extending slightly above the oil level and having a wick of suitable material placed thereon with its ends extending downward into the chambers 14 and 15 and thus feeding the oil from the chamber 14 into the chamber 15 by capillary attraction.

From the bottom of the chamber 15 a feed pipe 16 is attached to an L fitting 17 and an upright pipe 18 connects to an L fitting 19.

Said fitting 19 is secured to one end of a large horizontal pipe 20 which has its other end secured to a T fitting 21.

Within the pipe 20 and near the fitting 19 is rigidly secured a tight plug 22 which is of any suitable oil tight material, and which has near the bottom of the pipe 20 a tube 23 secured therein.

This tube 23 is of small diameter and of some springy material such as brass or steel and being rigidly secured at one end while its other end is free its free end can be deflected up and down like the free end of a spring.

The oil in its passage through the feed pipes is prevented from passage through the pipe 20 by the plug 22 and must travel through the small pipe or tube 23 which is placed in a slight upward angle in the pipe 20; and the discharge end of said tube 23 is formed with a lip 33 to insure a drip of the oil and prevent its flowing back down the outside of the tube.

It will thus be noted that the oil level will be on the same level as the discharge end of the tube 23 and by raising or lowering

ing the end of the tube 23 the oil level will be changed.

As the oil leaves the discharge end of the tube 23 it descends through the T fitting 21 5 the pipes 25 and 26 and L fitting 24 to the burner 27, which may be of any suitable type desired.

For regulating the oil level or the position of the discharge end of the tube 23 10 there is provided an adjusting screw 28 threaded into the end of a hinged arm 29 mounted in a support 30 which is secured on top of the T fitting 21.

The end of said adjusting screw 28 ex- 15 tends through a hole in said support 30 and the T fitting 21 and engages the upper side of the discharge end of the tube 23 for the purpose of pressing the same downward against the spring of said tube 23; said 20 screw being locked in any desired position by the lock nut 34; and it will be seen that the weight of said screw and the arm 29 are sufficient to depress the end of said tube 23 to its lowest point or limit.

To overcome this and to render the device 25 automatic there is placed between the hinged arm 29 and the support 30 a thermostatic wafer 31 which will by the changes in temperature raise or lower the arm 29 and the screw 28 allowing the end of the tube 23 to 30 raise to its normal position or be depressed by said screw 28 thus changing the oil level.

Referring to Figure 4, if it is desired to operate the device by hand and retain a

positive oil level, the wafer 31 is removed 35 and a hooked shaped lever 35 is pivoted at 36 to the pipe 20 with its hooked end ex- 40 tends downward through a hole in the pipe 20 and engaging the free end of the tube 23; while the other end of the lever 35 is adjustably secured to a bracket 37 by a pin in one of the holes 38.

Regarding the oil level; if the free end of the tube 23 is depressed the oil will flow with 45 greater speed, and if the end of the tube is raised the oil will flow slower, thus at all times producing an even flow of oil.

Having thus described my invention, what I claim as new and desire to secure by Letters Patent, is:

In an oil feeding device for wickless burners of the class described, in combination with an oil reservoir and a wickless burner, connected by suitable feed piping, of a horizontal feed pipe mounted in the 55 feeding system, a flexible tube mounted within said horizontal pipe at an angle therewith and having its intake end rigidly secured and its discharge end free to move, means for preventing the flow of oil through 60 said horizontal pipe, and means for adjusting the position of the free end of said tube within said pipe, for the purpose set forth and substantially as described.

In testimony whereof I hereunto affix my 65 signature.

ISAAC KENSEL EVANS.
